UNITED STATES PATENT OFFICE

LOUIS J. SAUER, OF OAK PARK, ILLINOIS, ASSIGNOR TO CHARLES H. JOY, SR., OF CHICAGO, ILLINOIS

DUPLICATOR

Application filed April 13, 1931. Serial No. 529,629.

This invention relates to duplicating machines and more particularly to carriage construction and control including automatic paper feeding and aligning mechanism cooperative therein, with special reference to that class of machines provided with a flat gelatinized printing surface over which a carriage having a suitable platen roller is arranged to travel.

10 The invention is particularly adapted for use in connection with machines in which paper or suitable cards may be inserted in the carriage and the platen roller impresses the original or the copy sheet on the gelatinized surface, which latter receives the impression from the original sheet and transfers it to the copy sheet. A structure somewhat similar to that in the present application is disclosed and claimed in my copending applications Serial No. 457,234, filed May 29, 1930, and Serial No. 486,608, filed October 6, 1930.

20 In positioning the original or the copy sheets on the gelatinized surface, it is necessary that the paper be accurately aligned with relation to the platen roller and the printing surface and that the sheets be fed to the gelatinized surface and under the platen roller in such a manner that a suitable margin will result. It is also desirable that means be provided whereby the original may be impressed on the printing surface and large numbers of copy sheets of various thicknesses may thereafter be fed into the machine and automatically positioned relative to the printing surface to provide the same margin on all of the copies regardless of the difference in thickness.

30 Heretofore, machines of this type have been unsatisfactory and unreliable and required a separate and careful adjustment for each thickness of paper in order to retain the same margin; also, when previous methods are used and stiff cards or paper are inserted in the machine, the sharp edge of the paper causes injury to the gelatin printing surface.

40 In my invention I have overcome the above and other objections and have provided an accurate and convenient means for feeding

either thin paper or comparatively stiff cards to the printing bed in such a manner that there is no tendency to injure the gelatin surface and have also provided an automatic aligning means for accurately aligning the 55 paper with the impression on the printing bed in such a manner as to provide the same registration thereon regardless of the thickness of paper used.

50 The embodiment of my invention, which will be later described in detail, contemplates a duplicating machine having a carriage for movement back and forth over a printing bed, and in which carriage is mounted the usual platen roller, which latter may be automatically lowered or raised by the lost motion of the carriage handle during the rest periods of the carriage and preparatory to starting or reversing the movement thereof.

60 While the platen roller is in the raised 70 position, paper, or a suitable card, is inserted between the platen roller and a yieldable pressure roller where it engages and is aligned by a rotary margin bar arranged to rotate about the platen roller. The handle is then 75 operated preparatory to moving the carriage to perform the printing operation, and the lost motion of the carriage handle simultaneously lowers the platen roller and rotates the margin bar to carry the paper around the 80 platen roller and into substantially parallel alignment with the printing surface, the platen roller being locked during a portion of its downward movement so as to feed the 85 paper by engagement with the yieldable pressure roller.

90 The rotary margin bar moves somewhat faster than the paper is fed, and, therefore, the paper will be released therefrom as soon as it has been fed under the platen roller to a position where its release will allow the paper to strike the gelatinized printing surface in substantially parallel alignment therewith so that the edge of the paper or card will not cut into or otherwise injure the surface, and the margin bar will continue its rotation to a position to allow the final part of the downward movement of the platen roller to press the paper snugly against the 95 printing surface.

100

An especially desirable feature of the present invention comprises a completely automatic margin-controlling paper feed mechanism, whereby paper or cards, varying 5 greatly in thickness, may be automatically delivered to the gelatinized surface to provide the same margin regardless of the thickness of the paper.

The invention also includes a completely 10 automatic platen clutch mechanism, whereby the platen roller may be locked during certain portions of its movement.

A further feature is the provision of a completely automatic margin-controlling paper 15 feed and a suitable margin bar paper guide cooperating therewith, all incorporated in the carriage of the duplicating machine and automatically operable by the single means operating the carriage.

20 I also provide means whereby the paper-feeding operation is completed before the movement of the carriage begins and wherein the paper-feeding operation for maintaining the same margin on paper of different thickness is controlled by the same directional 25 movement of the handle controlling the carriage.

My invention also includes a rotary margin bar and paper-aligning means cooperating 30 with an automatic platen control which will automatically guide the paper into aligned relation with the printing surface, thereby preventing injury to the gelatin when the paper is delivered to the surface and will align 35 the paper to provide the same margin on thick or thin paper.

A further important feature is the provision 40 of a simple and efficient means for the locking carriage against forward movement until the platen roll is in operative engagement with the printing bed.

I also provide a novel equalizing means 45 for the platen roller whereby the roller automatically adjusts itself to inequalities in the printing bed and whereby a constant pressure thereon is maintained during the printing operation.

Another object is the provision of convenient means whereby the movable platen roller 50 and its support is automatically locked in either the lowered printing position or in a raised position beyond the normal limit whereby the platen roller may be easily removed from or inserted in the carriage.

55 Further objects will appear from the detailed description and the appended claims.

In the drawings:

Figure 1 is a top plan view of a portion of a duplicating machine in which one embodiment of my invention is illustrated;

Fig. 2 is a transverse sectional view through the carriage operating handle, illustrating the locking mechanism, and taken on a line corresponding to line 2-2 of Fig. 1;

65 Fig. 3 is a detail transverse section on a

line corresponding to line 3-3 of Fig. 1 and illustrates the intermediate shaft support;

Fig. 4 is an elevation of the guide rod end of the carriage, the platen roller and a portion of the operating mechanism being shown 70 in dotted lines;

Fig. 5 is a transverse sectional view through the opposite end of the carriage, taken on a line corresponding to line 5-5 of Fig. 1;

Fig. 6 is a transverse sectional view 75 through the carriage, taken on a line corresponding to line 6-6 of Fig. 1, with the mechanism shown in position after the platen roller has been moved into contact with the gelatinized surface;

Fig. 7 is a transverse sectional view similar to that shown in Fig. 4, with the operating parts in raised position;

Fig. 8 is a sectional detailed view through the platen roller bearing and support mechanism, taken on a line corresponding to line 8-8 of Fig. 6;

Fig. 9 is a detailed perspective view of the platen roller clutch and platen roller bearing;

Fig. 10 is a perspective view of the pressure roller connecting link;

Fig. 11 is a perspective view of one end of the margin bar and stop link pivoted thereon;

Fig. 12 is a detailed perspective view of the pressure roller and bearing therefor;

Fig. 13 is a perspective view of the clutch end of the platen roller, the clutch engaging lugs being shown in section on a line corresponding to line 13-13 of Fig. 8;

Fig. 14 is a diagrammatic view illustrating the relative positions of the operating during the paper feeding operation: and

Fig. 15 is an enlarged diagrammatic view 105 illustrating the locking point of the platen roller to provide the same margin for thick or thin paper.

Referring to the drawings in detail, the embodiment illustrated comprises a duplicating machine having side frame members 1 and 2 on which is supported a bed plate 3 having a gelatinized printing surface 4 thereon. The gelatinized surface usually comprises a band or ribbon which is wound 110 on spools mounted at each end of the machine and by which the ribbon may be moved over the printing bed and secured in any desired position thereon, and then may be wound from one spool to another and stretched over the printing bed to provide a new printing surface. The spools are not shown as they form no part of the present invention.

A carriage 5 is supported for longitudinal movement over the printing bed and comprises a rectangular frame 6, which is preferably of comparatively heavy sheet metal, having a downwardly extending bracket 7 provided with outwardly extending bearings 8. These bearings are formed around a 125

bearing guide rod 9 which latter is longitudinally supported adjacent the side frame member 1. The alignment of the rod 9 provides for the accurate movement of the carriage back and forth over the printing bed, and the bearings 8 thereon also allow the carriage to be raised from the printing surface by rotation on the guide rod. The opposite end of the carriage is supported on the side frame 2 by means of a roller 10 which is pivoted on the end plate of the carriage.

By this construction the carriage may be moved back and forth over the printing surface or raised for inspection of the gelatin. A rock shaft 12 is pivotally mounted in the carriage end plates by means of suitable bearing screws 13 and is provided with arms 14 and 15 secured thereto for supporting a platen roller 16. The rock shaft 12 is also provided with an intermediate bearing support 12a secured to the side frame 6, as shown in Fig. 3.

The platen roller is provided at each end with reduced shaft extensions, as indicated at 17 in Fig. 8. A bearing hole 18 in the rock shaft arm 14 is arranged to receive one of the platen roller shaft extensions 17 and to provide a bearing therefor. The platen roller shaft extension 17a on the opposite end 30 of the platen is mounted in an open bearing slot 19 in the arm 15, as shown in Fig. 5. The arm 15 is provided with an arcuate surface 20 which is in alignment with a similar arcuate surface on a retaining member 21 secured 35 to the end of the carriage. By this construction, it will be obvious that when the rock shaft is operated to raise and lower the platen, the shaft extensions 17a will be retained in the bearing slot 19 by means of the arcuate 40 retaining member 21 during the normal movement of the platen roller. In Fig. 5 the arm 15 is illustrated in its normal raised position.

When it is desired to remove the platen roller it is only necessary to rotate the rock shaft 12 to raise the platen roller until the roller shaft extension 17a is above the surface 22 of the retaining member 21, when the shaft may be removed from the bearing slot 19 and the platen may be easily removed from the carriage. In order to operate the carriage over the bed surface and to operate the rock shaft to raise and lower the platen roller, a handle 23 is secured to the rock shaft 55 12.

The rock shaft 12 and the arms 14 and 15 thereon provide a movable frame or yoke pivoted on the carriage by means of the bearing screws 13, and the handle 23, being arranged to move this yoke and also providing the means whereby the carriage may be moved over the printing surface. The lost motion between the handle and carriage frame will automatically raise and lower the platen roller.

It is desirable that the platen roller should be locked in its lowered position when pressed against the gelatinized surface. The locking means comprises a rod 24 slidably mounted in the handle 23, as shown in Fig. 2, and normally held yieldably in raised position by means of a spring 25 engaging a push button 26 on the rod; an auxiliary spring 27 is also mounted in the handle 23 and arranged to be engaged by the button 26 when more than the normal movement of the rod is desired. The rod 24 extends through the rock shaft 12, and the lower end is slotted at 28 to receive an arcuate rocking plate 29, which latter is rigidly secured to the side plate of the carriage frame 6. The lower end of the rod is also provided with a lug 30, which is automatically engaged in a notch 31 in the plate 29 when the platen roller is lowered to the printing position.

When it is desired to raise the roller for the insertion of paper thereunder, the button 26 is pressed downwardly and the lug 30 will thereby be released from the notch 31. The handle is then moved to raise the platen roller 90 until the lug 30 engages a downwardly extending lug 32 on the plate 29. This movement of the lug 30 between the notch 31 and the lug 32 provides the normal lost motion between the platen roller and the carriage, 95 and when the handle is moved to a position to be stopped by the lug 32, the platen roller will be raised to the position indicated in Figs. 5 and 7.

When it is desired to remove the platen roller, the button 26 is pushed downwardly against the pressure of the auxiliary spring 27 sufficiently to allow the lug 30 to pass beyond and be retained by the stop lug 32, whereby the yoke arms 14 and 15 will be 105 raised and locked above their normal raised position and the bearing slot 19 in the arm 15 will be retained above the retaining member 21. The platen roller shaft extension 17a may then be removed from the bearing slot 110 19, and the platen roller may be easily removed from or inserted in the carriage. The normal lost motion of the platen roller, however, is limited by the movement of the locking lug 30 between the notch 31 and the stop 115 lug 32.

In order that the pressure of the platen roller against the printing surface may be equalized over its entire length, and to provide a uniform pressure regardless of inequalities in the printing surface, the yoke arms 14 and 15 are not rigidly secured to the rock shaft 12, but are loosely mounted thereon and yieldably connected to the rock shaft by means of upwardly extending arms 33 secured to the rock shaft and normally engaged between lugs 34 on the arms 14 and 15, and springs 35 also mounted thereon. The arms 33 are normally in engagement with the lugs 34, and when the shaft 12 is rotated in an 120 125 130 135 140

anti-clockwise direction the platen roller will be raised by the positive engagement of the arms 33 with the lugs 34. During the operation of the handle to cause the downward movement of the platen roller, the handle 23 will be moved slightly beyond the point of engagement of the platen roller with the printing surface, and in the locked position of the handle shown in Fig. 2, the springs 35 will be slightly compressed, (Fig. 6) allowing the free alignment of the platen roller with the printing surface and providing for a constant pressure therebetween.

The platen roller bearing arm 14 is provided adjacent the platen bearing with radially disposed, inwardly extending lugs 36, and the arm 15 is provided with similar lugs 37 adjacent the bearing slot 19. These lugs extend into slotted openings 38 in suitable pressure roller links 39, and provide a portion of the bearing therefor. A rotary margin bar 40 comprising a curved sheet metal plate 41 is provided with end plates 42 having outwardly extending bearing lugs 43 thereon, which latter also extend into the slotted link openings 38 to complete the bearing therefor. The margin bar end plates 42 are also provided with slots 44 in which the platen roller reduced shaft extensions 17 and 17a are engaged, the margin bar being mounted for independent rotation in the pressure roller links 39 by means of the bearing lugs 43. The margin bar is therefore rotatably supported in the links 39 and rotates around the platen roller shaft extensions 17 and 17a, which latter are engaged in the slots 44.

The rotation of the margin bar is caused by tumbler links 45, one of which is pivoted on each end of the margin bar at 46, the opposite ends of the links being pivoted to the carriage frame at 47. Rearwardly extending portions 48 of the links provide stops for engagement with the rock shaft 12 when the mechanism is in the raised position shown in Figs. 5 and 7. The margin bar and cooperating parts are retained rigidly in the raised position by engagement of the end plates 42 with pins 50 on the pressure roller connecting links 39.

A pressure roller 51 is provided with reduced bearing portions 52 which are engaged in elongated holes 53 in the links 39. The pressure roller is supported in bushings 54 on the shaft extensions 52. These bushings extend through elongated slots 55 in the ends of the carriage and are provided with grooved flanges 56, against which springs 57 are engaged to provide a yielding engagement of the pressure roller against the platen roller, the elongated holes in the links 39 allowing a slight movement of the pressure roller when engaged by the platen roller to allow for different thicknesses of paper. An inclined paper table 58 is secured to the frame substantially in alignment with the pressure roller.

The margin bar is provided with a shoulder 59 and a forwardly extending flange 60 to receive and engage a card or paper 61 when it is inserted between the platen roller and the pressure roller, as shown in Fig. 14.

It will be noted that when the platen roller is raised from the lowered position shown in Figs. 4 and 6 to the position shown in Fig. 7, the lugs 36 and 37 on the arms 14 and 15, respectively, will be brought into alignment with the restricted portion 62 of the slotted opening 38 in the pressure roller link 39, and the platen roller will be raised out of axial alignment with the margin bar, as shown in Figs. 5 and 7. Simultaneously the link 39 will be raised and the margin bar will be rotated by the tumbler links 45 to allow the reduced platen roller shaft extensions to pass upwardly through the slots 44 in the margin bar end plates. All of the margin bar mechanism will be rigidly held in the position shown in Figs. 5 and 7 by means of the spring-pressed links 39 and the tumbler stop 48, which latter engages the rock shaft 12, the margin bar end plates engaging the pins 50.

When paper is inserted between the raised platen roller and the pressure roller, it will be engaged against the margin bar, and the handle 23 is then moved forward to lower the platen roller and engage the paper against the pressure roller, the margin bar remaining in raised rigid position until the platen roller is lowered into axial alignment therewith.

In order to provide an automatic means for locking the platen roller during the time that the paper is engaged, I provide a clutch mechanism comprising an arcuate arm 63 pivoted at 64 on the platen roller supporting arm 14. A spring 65 is secured on the arm 14 at 66 and engages a rearwardly extending portion of the clutch arm to normally retain the clutch in engaged position. The arm 60 is provided with an outwardly extending clutch portion 68 having lugs 69 thereon. These lugs are arranged to engage an outwardly extending flange 70 on the platen roller when the clutch is engaged, and it will be noted that the spring 65 holds the clutch engaged, and prevents the rotation of the platen roller while it is being raised and lowered, except during those portions of the movement when the clutch is disengaged by means which will now be described.

When the platen roller is in its normal raised position, as indicated in Fig. 7, the arcuate clutch arm 63 is held in disengaged position by means of a roller 71 on the carriage frame. This disengagement of the clutch in its highest position allows the platen roller to be rotated, if desired, or it may be easily removed from or inserted in the carriage. The relative arrangement of the clutch arm 63 and the roller 71 is such that during the downward movement of the platen roller the arm 63 is released from the roller 71 and the clutch will

be engaged at a definite predetermined point approximately coinciding with the engagement of the platen roller with the thinnest paper used in the machine. The paper will 5 then be fed to a predetermined position, after which the pivoted end of the tumbler link 45 engages a lug 72 on the clutch portion 63 (Fig. 6), thereby rotating it on its pivot 64 and causing the disengagement of the clutch 10 and allowing the platen roller to rotate in its lowered position and while in engagement with the printing surface. A pin 65^a prevents the displacement of the clutch arm 63 if the handle is operated with the platen roller re- 15 moved.

In order to prevent the carriage from moving from its extreme forward position before the platen roller is in a printing position a lock has been provided for engagement with 20 the frame to retain the carriage against a stop 73 (Fig. 5), until the platen roller has been lowered, at which time the lock is automatically released and the carriage may then be moved to perform the printing operation. 25 The lock comprises a lever 74 pivoted on the frame at 47, and having a downwardly extending portion 75 arranged to engage in a notch 76 in the side frame when the carriage is against the stop 73. A spring 77 tends to 30 retain the lever 74 in locked position. The opposite end 78 of the lever 74 is in a position to be engaged by the arm 14 when the platen roller is lowered into printing position, thereby raising the locking portion 75 35 out of the notch 76, and allowing the carriage to be moved forward. As the carriage is returned to its original position against the stop 73, the lever 74 will be again engaged in the notch. Other notches 76^a in the side 40 frame 1 may be used, if desired, to control the stopping position of the carriage when it is desired to operate the carriage in various positions relative to the printing surface.

In order that paper of different thickness 45 may be used in such a manner as to provide the same margin and to accurately align on the gelatinized surface in the same position relative to the platen roller, it is desirable that the platen roller should lock against 50 rotation at the point at which it will engage the thinnest paper ordinarily used in the machine. This is illustrated in Fig. 15, in which a very thin paper is indicated by the full lines A and a very thick sheet of paper is 55 indicated by the dotted lines B. It will be obvious from Fig. 15 that if the platen roller 16 is locked, by means of the clutch just described, immediately upon its engagement with the thin paper A, the paper will be fed 60 downwardly during the further locked downward movement of the platen roller and the platen roller clutch will be released to prevent further feeding movement of the paper as soon as the paper has been carried 65 by the margin bar around the platen roller to

a position where it is in substantial alignment with the gelatinized surface. It will then be released and the margin obtained on all papers of similar thickness or of different thicknesses will be the same. 70

In order to automatically provide the same margin on very thick paper, as indicated by the dotted lines B, the platen roller locking adjustment need not be changed but the platen roller will be free to rotate and roll 75 on the thick paper until it has reached the same point as the point of engagement with the thin paper. At this point the platen roller will be locked and obviously the thick paper will then be fed to exactly the same 80 relative position and will be aligned on the gelatinized surface in exactly the same marginal relation as the thin paper.

In practice, the rotating margin bar passes 85 very close to the gelatinized printing surface, thereby carrying the paper into adjacent parallel relation to the surface, so that when it is released it does not strike the surface at an angle thereto. In the drawings the space between the margin bar and the 90 gelatinized surface has been exaggerated for purposes of illustration.

In a machine of this type it is desirable that the platen roller be as light as possible, and I therefore provide a hollow construction 95 comprising a thin metal tube 79 supported on suitable end plates, having the shaft extensions 17 and 17^a thereon, and the tube 79 being covered with a thin layer of resilient rubber-like material. 100

In some cases the equalizing feature of the platen roller support is not required, and the yoke arms 14 and 15 may then be secured rigidly to the rock shaft 12, and the springs 35 omitted. 105

While I have illustrated but one embodiment of my invention, it will be obvious that modifications may be made without departing from the spirit of the invention, and I desire, therefore, to be limited only by the 110 scope of the prior art and the appended claims.

Having thus described my invention, what I claim and desire to secure by Letters Patent of the United States is: 115

1. A device of the character described comprising a printing bed, a carriage arranged to travel over said bed, means for operating said carriage and having a lost motion relative thereto, a platen roller movable by said carriage operating means, a pressure roller, a movable margin bar, and clutch means cooperating between said platen roller and said carriage operating means to cause the cooperative action of said 120 rollers and said margin bar to feed sheets of different thickness to the same marginal position on said bed. 125

2. A device of the character described comprising a printing bed, a carriage ar- 130

ranged to travel over said bed, means for operating said carriage and having a lost motion relative thereto, a platen roller movable by said carriage operating means, a pressure roller, a movable margin bar, clutch means cooperating between said platen roller and said carriage operating means to cause the cooperative action of said rollers and said margin bar to feed sheets of different thickness to the same marginal position on said bed, and resilient equalizing means between said platen roller and said carriage operating means.

3. A device of the character described comprising a printing bed, a carriage arranged to travel over said bed, means for operating said carriage and having a lost motion relative thereto, a platen roller movable by said carriage operating means, a pressure roller, a movable margin bar, automatic means for locking said platen roller against rotation during the lost motion movement, said locking means cooperating with said margin bar to unlock said platen roller adjacent its printing position.

4. A device of the character described comprising a printing bed, a carriage arranged to travel over said bed, means for operating said carriage and having a lost motion relative thereto, a platen roller movable to and from said bed by said operating means, a rotatable margin bar, means for locking said platen roller against rotation during the lost motion movement, and means cooperative with said margin bar to unlock said platen roller for rotation adjacent said bed.

5. A device of the character described comprising a printing bed, a carriage arranged to travel over said bed, means for operating said carriage and having a lost motion relative thereto, a platen roller movable to and from said bed by said operating means, a rotatable margin bar, means for locking said platen roller against rotation during the lost motion movement, means cooperative with said margin bar to unlock said platen roller for rotation adjacent said bed, and means to unlock said platen roller for rotation in its raised position.

6. A device of the character described comprising a printing bed, a carriage arranged to travel over said bed, means for operating said carriage and having a lost motion relative thereto, a platen roller movable to and from said bed by said operating means, a rotatable margin bar, means for locking said platen roller against rotation during the lost motion movement, means cooperative with said margin bar to unlock said platen roller for rotation adjacent said bed, and means independent of said operating means to unlock said platen roller for free rotation in its raised position.

7. A device of the character described

comprising a carriage frame, a platen roller yoke mounted for relative movement therewith, a platen roller mounted for rotation on said yoke, a margin bar rotatable around said platen roller during said lost motion, a pressure roller, and means cooperative between said margin bar and said platen roller to control the rotation of said platen roller to cause the cooperation of said platen roller, said pressure roller and said margin bar to feed paper of different thickness to the same marginal position.

8. A duplicating machine of the character described comprising a printing bed, a carriage movable over said bed, a platen roller on said carriage and movable into and out of operative relation to said bed, a pressure means for paper engaging cooperation with said platen roller, a margin bar movable under said platen roller, and means cooperating between said margin bar and said platen roller to control the marginal relation of paper of different thickness on said printing bed.

9. In a duplicating machine of the character described, the combination with a printing bed of a carriage movable over said bed, a platen roller on said carriage and movable into and out of operative relation with said bed, a margin bar movable relative to said platen roller, means for locking said carriage relative to said bed, and a single means for controlling all of said operations.

10. In a duplicating machine of the character described, the combination with a printing bed of a carriage movable over said bed, a platen roller on said carriage and movable into and out of operative relation with said bed, a margin bar movable relative to said platen roller, means for locking said carriage relative to said bed, and a single means having a lost motion relative to said carriage for controlling all of said operations.

11. In a duplicating machine, a carriage arranged to travel over a printing bed, a carriage operating handle having a lost motion in the direction of movement of said carriage, a platen roller arranged to be raised and lowered by the lost motion of said handle, a pressure roller cooperating with said platen roller to feed paper therebetween during the downward movement of said platen roller, a rotary margin bar, means cooperating between said margin bar and one of said rollers and controlled by said handle for controlling the marginal relation of sheets of paper fed to said bed.

12. A device of the character described comprising a printing bed, a carriage arranged to travel over said bed, a rock shaft pivoted for lost motion relative to said carriage, arms on said rock shaft, a platen roller pivoted on said arms for movement therewith, clutch means on one of said arms and cooperating with said roller to lock said roll-

- er against rotation, a rotary margin bar pivoted in substantially axial alignment with said roller and having a lost motion relative thereto and arranged to be raised and lowered with said roller, a tumbler link for rotating said margin bar, said link operating to disengage said clutch when said roller is adjacent said bed, and a single handle for operating said rock shaft and said carriage.
- 10 13. In a duplicating machine of the character described, the combination with a printing bed of a carriage movable over said bed, a platen roller on said carriage and movable into and out of operative relation with said bed, a margin bar movable relative to said platen roller, and means for operating said platen roller and said carriage, means responsive to the position of said operating means and operative during a material range 20 of movement of said operating means for locking said carriage relative to said bed.
14. In a duplicating machine of the character described, the combination with a printing bed of a carriage movable over said bed, a platen roller on said carriage and movable into and out of operative relation with said bed, a margin bar movable relative to said platen roller, means for operating said platen roller and said carriage, and means responsive to the position of said operating means and operative during a material range of movement of said operating means for locking said carriage relative to said bed.
- 25 15. A device of the character described comprising a printing bed, a carriage arranged to travel over said bed, means for moving said carriage and having a lost motion relative thereto, said carriage moving means having a platen roller journaled therein, and means controlled by said carriage moving means and operative during a material portion of the range of lost motion of said carriage moving means for locking said carriage relative to said bed.
- 40 16. A device of the character described comprising a printing bed, a carriage arranged to travel over said bed, means for moving said carriage and having a lost motion relative thereto, and means operative during a material portion of the lost motion of said carriage moving means for locking said carriage relative to said bed and for automatically unlocking said carriage at a predetermined point in the range of lost motion of said carriage moving means.
- 45 17. A device of the character described comprising a printing bed, a carriage arranged to travel over said bed, means for moving said carriage and having a lost motion relative thereto, means operative during a material portion of the lost motion of said carriage moving means for locking said carriage relative to said bed and for automatically unlocking said carriage at a predetermined point in the range of lost motion of said carriage moving means.
- 50 18. In a duplicating machine of the character described, the combination with a printing bed of a carriage movable over said bed, a platen roller on said carriage and movable into and out of operative relation with said bed, means for operating said platen roller and said carriage, and means responsive to the position of said operating means and operative during a material range of movement of said operating means for locking said carriage relative to said bed.
- 55 19. In a duplicating machine of the character described, the combination with a printing bed of a carriage movable over said bed, a platen roller on said carriage and movable into and out of operative relation with said bed, means for operating said platen roller and said carriage, and means responsive to the position of said operating means and operative during a material range of movement of said operating means for locking said carriage relative to said bed, said operating means having a lost motion relative to said carriage.
- 60 20. In a duplicating machine of the character described, the combination with a printing bed of a carriage movable over the bed, a platen roller on said carriage and movable into and out of operative relation with said bed, common means for moving said platen roller into and out of operative relation with the bed and moving the carriage over the bed comprising a handle on the carriage having a lost motion rocking movement for moving the platen roller into and out of operative relation with the bed, and means for locking the carriage in its home position released by the rocking movement of the handle, said locking means being effective to lock the carriage in home position until the platen roller is in operative relation with the bed.
- 65 21. In a duplicating machine of the character described, the combination with a printing bed of a carriage movable over said bed, a platen roller on said carriage and movable into and out of operative relation with said bed, common means for moving said platen roller into and out of operative relation with the bed and moving the carriage over the bed, and means controlled by said common operating means for locking said carriage in its home position, said locking means being effective to hold the carriage in its home position until the platen roller has been moved substantially into operative relation with respect to said bed.
- 70 22. In a duplicating machine of the character described, the combination with a printing bed of a carriage movable over said bed, a platen roller on said carriage and movable

into and out of operative relation with said bed, means for operating said platen roller and said carriage, a margin bar for positioning the sheet on the printing bed, and means responsive to the position of said operating means and operative during a material range of movement of said operating means for locking said carriage relative to said bed.

In witness whereof, I have hereunto subscribed my name.

LOUIS J. SAUER.
